FORM BRACE

Dean C. Findley, Concord, Calif.

Application May 18, 1953, Serial No. 355,709

5 Claims. (Cl. 25—118)

The present invention relates to an improved adjustable brace for concrete forms and the like which is re-usable and may be rapidly installed and removed for engagement with forms of various sizes and on level or sloping terrain.

It is the custom when pouring concrete or the like to erect forms for retaining same until solidification thereof and to define the boundaries of the mixture. Such forms are ordinarily formed of lumber and do not comprise a permanent part of the structure but rather are intended for removal after the concrete has set into a solid state. Concrete forms include not only the form lumber defining a wall against which the concrete flows and presses during pouring but also bracing outside of the wall supporting same against the weight of the wet concrete. It is common practice to drive stakes or posts into the ground for supporting the concrete form wall as in the case of building foundations or slab concrete and further to provide wooden angle braces from such stakes into the ground or into attachment with further posts driven into the ground at a distance from the wall, inasmuch as the concrete form must have great strength to withstand the pressure of the wet concrete in even a fairly shallow building foundation for example.

The construction of conventional concrete forms as set out above is quite expensive and time-consuming and such forms are not readily adapted to disassembly after the concrete has hardened so that time is also lost in this operation and much of the form lumber is damaged in disassembly. Additionally, difficulty is encountered with standard forms, particularly on sloping terrain in the alignment of the forms in a horizontal plane so that the finished concrete foundation or the like will be level, for time-consuming manual lifting of the form lumber is necessitated to position same for nailing to the braces. Also, with the use of the conventional stakes, they must be driven along the building line to a considerable depth below the intended bottom of the concrete footings, and this operation often causes the trench walls to crumble before the forms are in position.

The present invention provides an improved adjustable brace adapted for engagement with lumber or other flat material forming a concrete form wall and adapted to position same in desired alignment or relation to the rest of the form. The improved brace is readily engageable with form lumber and also readily disengages same from hardened or set concrete and itself from the form lumber. It is contemplated that heavier form lumber may be employed with the improved brace of the present invention so as to be more readily reusable inasmuch as the brace provides for adjustment of the form lumber position, and further, the brace of the present invention provides maximum support for the form wall so as to preclude slipping or failure thereof and consequent damage to the setting concrete.

It is an object of the present invention to provide an improved brace adapted for ready engagement and/or disengagement with concrete forms.

Another object of the present invention is to provide

2

an improved form brace including means for positioning forms engaged thereby.

A further object of the present invention is to provide an improved form brace adapted for engagement with and support of concrete forms of varying size and providing means for readily removing such forms from hardened concrete poured therein.

A still further object of the present invention is to provide an improved form brace that is removably engageable with concrete forms and is adapted for anchoring to the ground or other footing whether same is aligned with or inclined with respect to the form.

Yet another object of the invention is to provide means of the character described which will obviate the need of driving the stakes along the margins or walls of the trench in which the concrete is to be poured.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

25 The invention is illustrated in the accompanying drawing wherein:

Figure 1 is a sectional elevation of a concrete slab building foundation with forms thereabout and supported by improved form braces in accordance with the present invention, there being two variations of the brace shown.

30 Figure 2 is a sectional elevation of the improved form brace shown at the left of Figure 1.

Figure 3 is a plan view of the improved form brace of Figure 2.

35 Figure 4 is a partial elevation of the embodiment of the form brace shown at the right of Figure 1.

Considering now the structural details of the invention, and referring to the drawings, there is shown an excavation in the ground 11 of a sloping lot for a concrete slab 12 such as those employed for buildings. This excavation is intended to be filled with concrete 12 which will extend above the ground level and must therefore be confined by forms 13 which are shown as vertically disposed timbers 14. The forms 13 may be made of two-inch-thick lumber 15 planks 14 with the plank width being substantially equal to the desired form height above ground. The concrete slab 15 is sealed against weather by a membrane 16 which is disposed within the excavation prior to pouring of the concrete and which is extended upward therefrom contiguous with the inner surface of the form 13. In addition to the vertical plank wall 14 the form 13 must have supporting members disposed in engagement with the form exterior to the excavation for preventing the form from collapsing outwardly when the wet concrete 12 is poured into the forms. This support is provided by improved form braces of the present invention which are disposed about the form at spaced intervals, and there is shown in Figure 1 braces 17 and 18 which are slightly different for the reasons noted below.

60 Considering now the structural details of one embodiment of the invention and referring to Figures 2 and 3, the improved adjustable brace 16 includes a flat elongated base member 18 having spaced transverse slots 19 therein and adapted for disposition upon the ground or other solid footing adjacent forms to be supported by the brace. As shown in Figure 1, the base member 18 may be secured to the ground 11 by iron or other structurally rigid spikes 21 which are preferably formed as narrow plates to mate with the slots 19 in base 18 and have right angle projections at the top thereof for engagement with the top surface of base member 18 for locking same in position against the ground. Pivotally-mounted at one end

of base member 18 is mounting means including a plate 22 connected to base 18 by a hinge 23, and either attached to or formed integral with plate 22 is a mounting block 24 which extends away from base member 18 and which has a bore therethrough substantially parallel to plate 22. A slide bar or pipe 26 slidably engages mounting block 24 through the bore thereof for movement relative thereto and a set screw 27 is threaded into mounting block 24 for engagement with slide bar 26 to lock same in any desired relation to mounting block 24. There is carried upon slide bar 26 an angle plate 28 which is adapted to engage and position a plank 14 of form 13 and angle plate 28 is formed with a straight center position disposed parallel to slide bar 26 and a pair of oppositely extending end portions of which the upper portion 29 is rigidly attached as by welding to the upper end of slide bar 26 in overlapping relation thereto. The lower portion 31 of angle plate 28 extends perpendicularly from the center portion thereof away from slide bar 26 so as to carry a form plank which then also rests against the center portion of angle plate 28. Preferably a barb 30 is provided on the upper side of plate portion 31 in order to hold the plank thereon.

There is provided, in addition to the above described elements of brace 16, means for angularly positioning the angle plate 28 thereof for disposing a plank carried thereby in desired vertical alignment. Such means include a turnbuckle 32 which is pivotally mounted upon the upper surface of base member 18 by a hinge 33 rigidly secured thereto at a distance from plate 22 and is pivotally mounted by a hinge 34 to the top portion 29 of angle plate 28 overhanging slide bar 26. All members of the brace 16 are formed of material having good structural strength, such as iron or the like, and rigid connection of the members may be insured by welding.

In operation, the brace 16 is first firmly secured to the ground or other steady footing as by driving spikes 21 through slots 19 in base member 13 into the ground 11 with the brace disposed with the angle plate 28 thereof in alignment with the outer edge of the form 13 to be braced. The slide bar 26 is then slid vertically within mounting block 24 to position the angle plate 28 at the desired height and after locking slide bar 26 in position relative to mounting block 24 by set screw 27 a plank or timber may be placed edgewise upon angle plate 28 with the lower portion 31 thereof disposed beneath and supporting the plank 14. Vertical alignment of the form plank is obtained by turning turnbuckle 32 which thereby pivots angle plate 28, slide bar 26, mounting block 24 and plate 22 about the bottom of plate 22 upon hinge 23. It will be appreciated that no set sequence of operations is necessary to position the form plank carried by the brace but that, whatever the manner of use, the brace operates to carry the form plank and to easily vary both the vertical position thereof and the vertical alignment thereof. Normally a number of braces would be employed at spaced intervals along a form to be supported and aligned thereby and there may be provided in the central portion of angle plate 28 a number of holes by means of which planks may be affixed thereto as by nails when it is desired to dispose the form off vertical or sloping outward at the bottom. It is to be noted that no portion of the angle plate is required to be driven into the ground, particularly along the building line or trench walls. Thus there will be no danger of such walls crumbling during the application of the stake before the form boards are placed in position.

Attention is invited to the fact that with the brace in engagement with a form plank 14, as shown in Figure 1, for example, wherein the plank is vertically aligned, the angle plate 28 and form plank 14 carried thereby may be rotated about hinge 23 to remove the form from concrete that has set. Also by loosening the set screw 27 on mounting block 24, the slide bar and angle brace may be readily lifted and rotated as by hand or by placing a pick or the

like beneath a convenient part of angle plate 28 and lifting. The form is thus readily removed from the concrete and this operation is additionally simplified by the membrane 15 between the form and concrete which prevents adherence of concrete and form.

While provision is made for vertically positioning the form supported by the improved brace 16 there are instances where quite high forms must be supported so that a longer angle plate 28 is desirable. Such a situation is illustrated in Figure 1 wherein the foundation form at the lower end of a sloping lot is required to be higher so that a horizontal concrete slab can be poured thereon and the brace 17 there shown is modified to provide the requisite support. This brace 17, as shown in part in Figure 4, includes an angle plate 36 having an elongated center portion to accommodate and support form lumber such as a 2 x 12 plank. Rather than requiring separate braces for both shallow and deep forms the present invention provides in brace 17 a modified form wherein the angle plate 36 has the top portion thereof rigidly secured to the top of a slide bar 26 as in brace 16 but has the upper hinge 37 for turnbuckle 32 secured to a slide block 38 rather than to the mounting block 24 as in brace 16. Thus the brace 17 is identical to brace 16 except for the provision of an elongated slide bar 26 with a slide block 38 slidably engaging same above mounting block 24 and carrying the upper turnbuckle hinge 37. Also, there is provided an additional set screw 39 which is threaded into slide block 38 for engagement with slide bar 26 to lock slide block 38 in desired position thereon. It will be appreciated the brace 17 is operated the same as brace 16 except that the upper end of turnbuckle 32 is displaceable from the top of slide bar 26 so that a longer slide bar and angle plate may be employed.

What is claimed is:

1. An improved form brace comprising a base member adapted for mounting upon the ground carrying means pivotally mounted at one end of said base member, and including an angle plate slidably, with respect to said base member and having a lower flange adapted to engage and support a form adjacent the lower edge thereof, and threaded means pivotally connected between said base member and said carrying means at a distance from the pivotal connection therebetween for adjusting the angular disposition of said carrying means.

2. An improved form brace comprising a base member, a plate pivotally connected to said base member, a slide bar slidably engaging said plate, an angle plate rigidly attached to said slide bar for supporting a form, and threaded means pivotally connected to said base member and to said angle plate for varying the angular relation of said base and plate.

3. An improved form brace comprising a base member, an angle plate having two portions extending normal to each other and adapted for disposition with one portion thereof beneath a form plank, a plate pivotally mounted upon said base member, a slide bar rigidly secured to said angle plate and slidably mounted upon said plate for varying the relative disposition of said base member and angle plate, and threaded means connected between said base member and said slide bar for varying the relative alignment of said base member and angle plate whereby a form plank carried by said angle plate is readily positionable relative to said base member.

4. An improved form brace comprising a base member adapted to be rigidly secured to the ground, a plate pivotally mounted at one end of said base member, a mounting block secured to said plate and having an elongated aperture therethrough substantially parallel to said plate, a slide bar slidably engaging said mounting block through the aperture therein, locking means on said mounting block for maintaining a predetermined relative position of said slide bar and said block, an angle plate rigidly secured to said slide bar for movement therewith and including a first portion extending longitudinally of

said bar and a second portion extending substantially normal thereto away from said base member whereby said angle plate is adapted to engage and carry a form plank, and a turnbuckle pivotally connected to said base member and to said angle plate for varying the relative angular disposition of said angle plate and base member to align a form plank carried by said angle plate.

5. An improved form brace comprising a base member adapted for rigid mounting, mounting means pivotally connected to one end of said base member and having an elongated aperture therein, a slide bar slidably engaging said mounting means through the aperture therein, locking means for securing said slide bar in fixed relation to said mounting means, an angle plate rigidly affixed to the top of said slide bar and extending along said slide bar 10

with a right-angle portion extending away from said slide bar and adapted to extend beneath a form plank for carrying same, a slide block mounted upon said slide bar in slidable engagement therewith and having locking means for rigid attachment to said slide bar, and a turnbuckle pivotally mounted upon said base member and said slide block for adjusting the alignment of said angle plate and a form plank carried thereby.
